By Wilmarth H. Thurston,

ATTORNEY.

UNITED STATES PATENT OFFICE.

JONATHAN C. MELOON, OF PROVIDENCE, RHODE ISLAND, ASSIGNOR TO GENERAL FIRE EXTINGUISHER COMPANY, OF NEW YORK, N. Y., A CORPORATION OF NEW YORK.

FUSIBLE DEVICE.

1,093,063.

Specification of Letters Patent. Patented Apr. 14, 1914.

Application filed March 28, 1912. Serial No. 686,790.

To all whom it may concern:

Be it known that I, JONATHAN C. MELOON, of the city and county of Providence and State of Rhode Island, have invented 5 certain new and useful Improvements in Fusible Devices; and I do hereby declare the following specification, taken in connection with the accompanying drawings, forming a part of the same, to be a full, clear, 10 and exact description thereof.

The invention relates to a fusible device adapted to be employed in connection with automatic fire extinguishing apparatus, as for example to hold open fire-doors or shutters or in other relations where a fusible link 15 is employed.

The object of the invention is to strengthen the fusible solder-joint between the members of the device without diminishing 20 the sensitiveness of the device to heat and at the same time to facilitate the free flow of the solder over all of the opposing surfaces.

To that end the invention consists in the 25 novel construction and combination of parts hereinafter described and claimed and more particularly set forth in the claims.

In describing the invention reference will be made to the accompanying drawings, in 30 which—

Figure 1 is a top plan view of a fusible device embodying the invention in its preferred form. Fig. 2 is an edge view. Fig. 3 is a transverse sectional view on line $x-x$, 35 Fig. 1. Fig. 4 is a plan view of one of the members of the fusible device. Fig. 5 is an edge view of the same. Fig. 6 is a plan view of the other member. Fig. 7 is an edge view of the same. Figs. 8, 9, and 10 are 40 plan views of modified forms. Fig. 11 is a longitudinal sectional view on line $y-y$, Fig. 10.

Referring to the drawings, the fusible device consists of two members 1 and 45 2 adapted to be secured together by fusible solder. The member 1 is a double or two-part member and the member 2 is a single or one-part member which is constructed and adapted to be inserted between 50 the two-part member and soldered thereto. The double member 1 is preferably formed from a piece of sheet metal of double length 55 folded upon itself and provided adjacent the folded end with an eyelet 3 which furnishes means for attaching a chain or wire thereto.

The single member 2 is likewise provided with a similar eyelet 4. The portions of both members 1 and 2 which are arranged and adapted to engage each other are provided with a series of transverse holes or perforations 5 which register with each other. These holes 5 furnish egress for the air when the parts are squeezed together in the soldering operation, thereby insuring a free flow of the solder over all of the opposing surfaces and the solder flows into said holes and is formed into a series of interlocking transverse tongues or projections which serve to increase the strength of the link against tensile strain.

Both legs of the two part member 1 are preferably provided upon one side with a series of indentations 6 which produce a series of protuberances 7 upon the opposite side, as shown in Fig. 5. The one-part member 2 is also provided on one side with a series of similar indentations 8 which produce a series of protuberances 9 upon the opposite side, as shown in Fig. 7. These indentations and protuberances are so arranged and located that when the two members 1 and 2 of the link are assembled together the series of protuberances 9 upon one side of the one-part member 2 will enter the series of indentations 6 in one leg of the two-part member 1, while the series of indentations 8 in the opposite side of said one-part member 2 will be engaged by the series of protuberances 7 upon the other leg of said two-part member 1, as shown in Fig. 3. 90 These indentations and resulting protuberances provide interlocking means between the two members 1 and 2 formed from the metal of the members themselves and thus serve to still further increase the strength of the link against tensile strain. It is preferred to form the indentations and resulting protuberances conico-hemispherical in shape with rounded or inclined sides so that when the solder fuses the engaged surfaces of said indentations and protuberances will have a cam-like action, thereby facilitating the separation of the two legs of the two-part member and the consequent separation of the two members 1 and 2 when the solder is fused.

As shown in Fig. 1, it is preferred to employ both a series of indentations and protuberances and also a series of holes 5, said holes being formed both in the protuber-

ances and between them, but if desired the holes 6 may be formed only in said protuberances, as shown in Fig. 8, or only between said protuberances as shown in Fig. 10.

5 Figs. 10 and 11 show a modified construction in which each of the two legs of the two-part member 1 is provided with an indentation 6' on its inner side, while the one-part member is provided with two indentations 8' one on each side thereof, thereby producing protuberances 9' upon opposite sides, which protuberances 9' are so arranged and located that when the two members 1 and 2 of the link are assembled together, 15 one of the protuberances 9' on the one-leg member 2 will enter the indentation 6' in one of the legs of the two-part member 1, while the other protuberance 9' will enter the indentation 6' in the other leg of the 20 two-part member 1, as shown in Fig. 11.

What I claim as my invention and desire to secure by Letters Patent is:

1. An article of the character described comprising a two-part member having two legs and provided with an indentation in one side of one of the legs, and a one-part member adapted to be inserted between the legs of said two-part member and provided with an annular protuberance in one side 30 arranged to register with the indentation in the leg of said two-part member.

2. An article of the character described comprising a two-part member having two legs and provided with a conico-hemispherical indentation in one side and a conico-hemispherical protuberance in the opposite side of each leg, and a one-part member adapted to be inserted between the legs of said two-part member and provided with a 40 protuberance on one side arranged to enter the indentation in one leg of said two part member and provided with an indentation on the opposite side arranged to be engaged by the protuberance upon the other leg of 45 said two-part member.

3. An article of the character described comprising a two-part member having two legs and provided with a series of conico-hemispherical indentations in one side and 50 a series of conico-hemispherical protuberances in the opposite side of each leg, and

a one-part member adapted to be inserted between the legs of said two-part member and provided with a series of protuberances on one side arranged to enter the indentations in one leg of said two-part member and provided with a series of indentations in the opposite side arranged to be engaged by the series of protuberances upon the other leg of said two-part member. 55 60

4. An article of the character described comprising a two-part member having two legs and provided with a series of indentations and a series of protuberances in each leg and a series of holes arranged both in and between said protuberances, and a one-part member adapted to be inserted between the legs of said two part member and provided with a series of protuberances arranged to enter the indentations in one leg 65 of said two-part member, a series of indentations arranged to be engaged by the protuberances upon the other leg of said two-part member and a series of holes in and between said protuberances arranged to register with the holes in both legs of said two-part member. 70 75

5. An article of the character described comprising a two-part member having two legs and provided with an eyelet extending through both legs of said two-part member and an annular indentation in one of said legs having a cam-surface, and a one-part member adapted to be inserted between the legs of said two-part member provided with an annular protuberance having a cam surface arranged and adapted to engage the cam surface on the indentation in said two-part member. 80 85

6. An article of the character described comprising a two-part member having two legs and provided with an indentation in one of the legs of said two-part member, and a one-part member adapted to be inserted between the legs of said two-part member and provided with a protuberance inclosed on all sides and adapted to engage the indentation in said two-part member. 90 95
